(57) **CLAIM**

The ornamental design for a headwear as shown and described.

DESCRIPTION

FIG. 1 is a front view of a headwear according to a first embodiment of the claimed design.

FIG. 2 is a rear view of the headwear of FIG. 1.

FIG. 3 is a right side view of the headwear of FIG. 1.

FIG. 4 is a left side view of the headwear of FIG. 1.

FIG. 5 is a top view of the headwear of FIG. 1.

FIG. 6 is a bottom view of the headwear of FIG. 1.

FIG. 7 is a front view of a headwear according to a second embodiment of the claimed design.

FIG. 8 is a rear view of the headwear of FIG. 7.

FIG. 9 is a right side view of the headwear of FIG. 7.

FIG. 10 is a left side view of the headwear of FIG. 7.

FIG. 11 is a top view of the headwear of FIG. 7; and,

FIG. 12 is a bottom view of the headwear of FIG. 7.

The short-dash broken lines in the drawings illustrate stitching that forms no part of the claimed design.

The cross-hatch shading shown at the rear of the crown of the headwear is included in FIGS. 8-12 to show contrasting materials of the headwear, where the cross-hatch shading indicates contrast in material, namely material appearance, relative to other portions of the crown that do not include the cross-hatch shading. Any pattern formed by the cross-hatch shading forms no part of the claimed design.
